UNITED STATES PATENT OFFICE.

LEVI W. LOMBARD, OF MATTAPAN, MASSACHUSETTS, ASSIGNOR TO CENTRIFUGAL GUN CORPORATION, A CORPORATION OF MASSACHUSETTS.

CENTRIFUGAL GUN.

1,420,660.

Specification of Letters Patent. Patented June 27, 1922.

Application filed March 11, 1918, Serial No. 222,478. Renewed November 9, 1921. Serial No. 514,120.

To all whom it may concern:

Be it known that I, LEVI W. LOMBARD, a citizen of the United States of America, and a resident of Mattapan, in the county of 5 Suffolk and State of Massachusetts, have invented certain new and useful Improvements in Centrifugal Guns, of which the following is a specification.

This invention relates to centrifugal guns 10 and has for its object the provision of means in a device of this character for starting a ball projectile at a low rate of speed and constantly increasing the speed until it is finally ejected at a high velocity.

15 Another object of the invention is the provision of means whereby the delivery of the ball projectiles to the propelling member is limited to a single ball for each revolution of said propelling member.

20 A further object of the invention is the provision of means for continuously supplying projectiles to the propelling devices.

The invention consists primarily of a 25 revoluble disk enclosed in a casing having a tangential discharge opening in its periphery, said disk having a spiral rib in the path of the inner end of which a projectile is adapted to be fed at each revolution of said disk.

30 The invention further consists of certain novel features of construction and arrangement of parts which will be fully understood by reference to the description of the drawings and to the claims to be hereinafter 35 given.

For the purpose of illustrating the invention one preferred form thereof is illustrated in the drawings, this form having been found to give satisfactory and reliable 40 results, although it is to be understood that the various instrumentalities of which the invention consists can be variously arranged and organized and the invention is not limited to the precise arrangement and organization 45 of these instrumentalities as herein shown and described, except as required by the scope of the appended claims.

Of the drawings:

Figure 1 represents an elevation of a machine embodying the principles of the present invention.

Figure 2 represents a partial vertical section of the same on line 2, 2 on Fig. 1.

Figure 3 represents a vertical section of

the projectile hopper and feeding device on 55 line 3, 3, on Fig. 1.

Figure 4 represents a horizontal section of the same on line 4, 4, on Fig. 1.

Figure 5 represents an inverted plan of the casing cover. 60

Figure 6 represents a plan of the machine.

Figure 7 represents a plan of the casing with the cover removed and showing in plan the revoluble disk.

Figure 8 represents a section of the mechanism for delivering the projectiles to the interior of the casing, and 65

Figure 9 represents a section of the device for limiting the supply of projectiles to the interior of the casing to one for each 70 revolution of the revoluble disk.

Similar characters designate like parts throughout the several figures of the drawings.

In the drawings, 10 is a base or standard 75 provided with upwardly extending arms 11 having at their upper ends bearings 12 in which are mounted the trunnions 13 of an oscillating frame 14 having mounted therein an electric motor 15 adapted to rotate the 80 shaft 16 at a very high rate of speed.

One of the trunnions 13 has secured thereto a gear segment 17 meshing with a worm 18 secured to and revoluble with a shaft 19 mounted in bearings 20 on a bracket 21 secured to one of the arms 11. 85

The bracket 21 is provided with a receptacle 22 adapted to contain oil in which the worm 18 is adapted to be rotated by the handle 23 on the rear end of the shaft 19. 90

The axis of the frame 14 and motor shaft 16 may be brought to any desired inclination by rotating the worm 18 and then locked in adjusted position by the set screw 24 threaded in a boss 25 extending from one of the 95 bearings 20, the inner end of said screw 24 impinging upon the shaft 19 and preventing its further rotation.

The motor 15 may be of any usual construction having secured to its rotating 100 member the shaft 16 provided with a peripheral flange 26, an enlarged hub 27 and a reduced upwardly extending projection 28.

A disk 29 is secured to the flange 26 and rotates therewith, said disk being enclosed 105 within a casing formed of a bottom plate 30, a cover plate 31 and an annular member 32 interposed between said plates.

The bottom plate 30 has secured to its under face a plurality of clips 33 coacting with an annular flange 34 on the upper end of the frame 14.

5 These clips 33 prevent the displacement of the casing 30, 31, 32, while permitting said casing to be oscillated about the axis of the shaft 16 by means of the arm 35 having a bifurcated end 36 in which is revolvably 10 mounted the handle 37.

A sight bar 38 having a front sight 39 and a rear sight 40 is pivoted at 41 to the casing cover 31, said bar 38 being adjustable about the pivot 41 and adapted to be clamped 15 in adjusted position by means of the clamping member 42 extending through the curved slot 43 in a lateral arm 44 on said bar 38.

By means of the sights 39 and 40 the gun 20 may be aimed at the proper target and by adjusting the bar 38 due allowances may be made for windage, drift, and other conditions affecting the flight of the projectile.

The cover plate 31 is provided with a pointer 45 coacting with the graduations 46 25 on the arm 44 thereby providing a means for more accurately adjusting the sight bar.

A pointer 47 is placed on a bearing 12 coacting with the graduations 48 on the hub of the gear 17 thereby providing a means for 30 more accurately regulating the elevation of the gun.

The disk 29 is provided upon its upper face with two spiral ribs or members 49 the 35 operating walls of each of which is provided with an inserted hardened member 50 with its exposed face provided with a semi-cylindrical groove as indicated at 51.

The operating grooved walls of the ribs 40 49 have a constantly increasing pitch from their inner ends to the outer edge of the disk 29 where said ribs terminate.

The balls or projectiles to be fired will be delivered into the interior of the casing 30, 31, 32 in the path of the inner end of a spiral 45 rib 49 and as the disk 29 is rotated at a very high rate of speed the ball projectile will roll along the groove 51, the speed thereof being constantly increased as it moves outward along the operating wall 50 of the 50 rib 49.

The speed of the ball projectile is not only increased on account of the greater distance it moves from the center of the disk, but also on account of the peculiar shape of the said 55 spiral ribs 49 with the constantly increasing pitch of its operating wall 50.

Only one spiral rib 49 is used at a time, a ball projectile being delivered to said rib at each revolution of the disk 49 and means is 60 provided which prevents more than one ball being delivered into the interior of the casing 30, 31, 32 at each revolution of the disk 29.

The second rib 49 is used to balance the 65 rib 49 that is in action, but if the active rib

49 becomes injured in any manner the disk 29 may be removed from the flange 26 and then secured again to said flange in a position diametrically opposed to its former position.

When the disk has been thus changed the inactive rib will become active and the other will be used no longer.

Centrally disposed in the cover 31 and secured thereto is a tubular member 52 having 75 near its upper end an annular groove 53 into which extend the reduced ends of screws 54 mounted in a tubular cap 55. This construction permits the casing 30, 31, 32 to be oscillated without moving the cap 55.

From the cap 55 extends a projectile tube 56 through which the ball projectiles 57 are adapted to pass from the hopper 58 to the interior of the casing 30, 31, 32.

Near the cap 55 the tube 56 has a slot 59 85 cut therein through which extends a spring finger 60 to retard the movement of the balls 57 through said tube when there is no pressure behind them, it being obvious, however, that when pressure is applied to the rear of 90 the column of balls the spring finger 60 will be lifted and permit the balls to enter the passage 61 in the safety lock 62.

The safety lock 62 is adapted to be oscillated in the cap 55 thereby permitting the 95 upper end of the passage 61 therethrough to register with the end of the tube 56 as shown in Fig. 8 or to be moved into the position shown in Fig. 1, in which position the passage 61 is out of register with the end of 100 tube 56 and no more balls can pass from said tube through the passage 61 into the upper end of the tubular member 52.

The safety lock 62 may be clamped in either of its positions by means of the set 105 screw 64 having a pointed end adapted to enter indentations in the periphery of the lock 62, and thereby accurately register the same and prevent any accidental displacement of said lock while the machine is in 110 operation.

The tube 56 is curved around the edge of the ring 32 and the lower end 65 thereof is inserted in the hub 66 of the base plate 67 of the projectile hopper 58 and is free to 115 oscillate therein when the casing 30, 31, 32 is oscillated about the axis of the trunnions 13.

The lower end of the tube 56 registers with a hole 68 in the plate 67 said hole 120 communicating with a groove 69 in the upper face of said plate 67, said groove gradually decreasing in depth until at its opposite end the bottom thereof is in alignment with the upper face of said base plate 67.

The groove 69 is concentric to the center 125 of the base plate 67 which is secured to a bracket 70 having bearings 71 in which is mounted a revolute shaft 72 having an operating handle 73 secured to its lower 130

end and a cone-shaped revoluble member 74 secured to its upper end within the hopper 58 superimposed upon the base plate 67.

The lower part of the hopper 58 is cone-shaped at 75 with its inner wall conforming to the inclination of the periphery of the revoluble member 74. Surrounding the upper part of the revoluble member 74 the hopper 58 is formed cylindrical as at 76 and the upper part of said revoluble member 74 is cut away as at 77.

The entire periphery of the revoluble member 74 is provided with a plurality of upwardly extending grooves 78 into which 15 the balls in the hopper 58 are received and carried around in the lower cone-shaped portion 75 of the said hopper until they drop into the groove 69.

Owing to the constantly increasing depth 20 of the groove 69 it is obvious that as the operator continues to revolve the member 74 the balls in the groove 69 will be forced through the hole 68 and tube 56 into the passage 61 of the safety lock 62 from the 25 lower end of which said balls pass into the tubular member 52.

The upper end of the bore of the tubular member 52 is cylindrical as at 79 and below this cylindrical portion is formed a helical 30 groove 80 having a plurality of turns of the same depth and communicating with an enlarged groove 81 at the lower end.

The upward projection 28 of the shaft 16 extends into the bore of the tubular member 52 and is provided with a curved groove 82 the wall at the upper end of which registers with the cylindrical portion 79 of the bore of the tubular member.

The balls 57 when they are delivered from 40 the tube 56 into the passage 61 pass from the lower end of said passage into the cylindrical opening 79 which is in axial alignment with the shaft 16.

When a ball 57 comes into contact with 45 the shoulder 83 formed in the curved groove 82 it will be thrown out of the center of the bore of the member 52 and as the projection 28 rotates about the axis of the shaft 16 the ball 57 will be moved along the helical groove 80 into the lower enlarged groove 81 one portion of the said ball during this movement being positioned in the curved groove 82.

When the ball 57 reaches the lower part of 55 the groove 82 it will be delivered onto the upper face of the disk 29 in the path of movement of the spiral rib 49 which with the disk 29 rotates in the direction of the arrow *a* on Fig. 7.

As the disk 29 is rotated at a high rate 60 of speed the ball 57 will move along the spiral groove 51 with its speed constantly increasing until it reaches the extreme end of the spiral rib 49 when it will be ejected at a high velocity through the tangential

discharge opening 84 in a direction indicated by the dotted line 85.

For convenience in assembling the casing 30, 31, 32 so that the discharge opening 84 will be properly positioned relatively to the active spiral rib 49, the ring 32 is provided with a plurality of spaced holes 86 for each bolt 87 thereby providing a means whereby the bolts 87 may be removed, the ring 32 adjusted as desired and the bolts 87 again 75 inserted to lock the plates 30, 31 and ring 32 together.

To facilitate this adjustment of the ring 32, said ring is provided with a plurality of graduations 88 opposite one set of 80 holes 86.

When it is desired to use the gun it may be aimed by means of the handle 37, elevated or depressed by the handle 23, and a constant supply of ball projectiles delivered to the 85 interior of the casing 30, 31, 32 by the rotation of the handle 73.

When the motor shaft 16 is rotated at the desired high rate of speed the safety lock 62 is opened and the balls 57 will be permitted to enter the bore of the tubular member 52 and pass along the curved groove 82 and its coacting helical grooves 80, 81 and finally delivered therefrom in advance of the inner end of the rib 49 which will finally 95 eject it from the casing as described.

It is believed that the operation and many advantages of the invention will be fully understood without further description.

Having thus described my invention, I claim:

1. In a device of the class described, a revoluble plate; a spiral rib on one face thereof; a hardened grooved member set 105 into the inside wall of said rib; and means for directing a ball to the inner end of said spiral rib.

2. In a device of the class described, a revoluble shaft; a disk secured thereto; a spiral rib thereon; a projection from the shaft extending through said disk and having a curved groove therein terminating at the inner end of the operating wall of said spiral rib; a non-revoluble member positioned over said projection and having a helical groove therein coacting with said curved groove; and means for feeding balls intermittently from the lower end of said non-revoluble member.

3. In a device of the class described, a revoluble shaft; a disk secured thereto; a spiral rib thereon; a projection from the shaft extending through said disk and having a curved groove therein terminating at 125 the inner end of the operating wall of said spiral rib; a non-revoluble member positioned over said projection and having a helical groove therein coacting with said curved groove; a tube adapted to deliver 130

balls to the upper end of said non-revolute member; and means for retarding the movement of said balls through said tube.

4. In a device of the class described, a revolute shaft; a disk secured thereto; a spiral rib thereon; a projection from the shaft extending through said disk and having a curved groove therein terminating at the inner end of the operating wall of said spiral rib; a non-revolute member positioned over said projection and having a helical groove therein coacting with said curved groove; a tube adapted to deliver balls to the upper end of said non-revolute member; and a spring finger for retarding the movement of said balls through said tube.

5. In a device of the class described, a revolute shaft; a disk secured thereto; a spiral rib thereon; a projection from the shaft extending through said disk and having a curved groove therein terminating at the inner end of the operating wall of said spiral rib; the upper end of said groove being provided with a shoulder adapted to force a ball out of alignment with the axis of said shaft; and means coacting with said groove for feeding a ball into the path of said spiral rib.

30 6. In a device of the class described, a revolute shaft; a disk secured thereto and revolute therewith; a casing for said disk adapted to be oscillated and having a peripheral discharge opening; a spiral member 35 on said disk for projecting a ball through said peripheral opening; a centrally disposed tubular member secured to and projecting through the upper wall of said casing; a non-revolute tubular cap on the upper end of said tubular member; and a tube adapted to deliver balls to said tubular cap.

7. In a device of the class described, a revolute shaft; a disk secured thereto and revolute therewith; a casing for said disk adapted to be oscillated and having a peripheral discharge opening; a spiral member on said disk for projecting a ball through said peripheral opening; a centrally disposed tubular member secured to and projecting through the upper wall of said casing; a non-revolute tubular cap on the upper end of said tubular member; a tube adapted to deliver balls to said tubular cap; and a safety lock in said cap provided with 55 a passage therethrough for said balls.

8. In a device of the class described, a revolute shaft; a disk secured thereto and revolute therewith; a casing for said disk adapted to be oscillated and having a peripheral discharge opening; a spiral member on said disk for projecting a ball through said peripheral opening; a centrally disposed tubular member secured to and projecting through the upper wall of said cas-

ing; a non-revolute tubular cap on the upper end of said tubular member; a tube adapted to deliver balls to said tubular cap; and an oscillating safety lock in said cap provided with a passage therethrough for said balls.

9. In a device of the class described, a revolute shaft; a disk secured thereto and revolute therewith; a casing for said disk adapted to be oscillated and having a peripheral discharge opening; a spiral member on said disk for projecting a ball through said peripheral opening; a centrally disposed tubular member secured to and projecting through the upper wall of said casing; a non-revolute tubular cap on the upper end of said tubular member; a tube adapted to deliver balls to said tubular cap; an oscillating safety lock in said cap provided with a passage therethrough for said balls; and means for clamping said safety lock to said cap.

10. In a device of the class described, the combination of a casing having a peripheral discharge opening; a revolute disk within said casing provided with means for projecting a ball through said opening; means for feeding balls into the said casing at a point at one side of the axis of rotation of said disk; means for rotating said disk at a high rate of speed; a bar adjustably secured to said casing and movable parallel to the face thereof; and sights on said bar.

11. In a device of the class described, the combination of a casing having a peripheral discharge opening; a revolute disk within said casing provided with means for projecting a ball through said opening; means for feeding balls into the said casing at a point at one side of the axis of rotation of said disk; means for rotating said disk at a high rate of speed; a bar pivotally secured to said casing and movable parallel to the face thereof; and sights on said bar.

12. In a device of the class described, the combination of a casing having a peripheral discharge opening; a revolute disk within said casing provided with means for projecting a ball through said opening; means for feeding balls into the said casing at a point at one side of the axis of rotation of said disk; means for rotating said disk at a high rate of speed; a frame on which said casing is mounted; trunnions therefor; a motor in said frame adapted to impart rotary movement to said revolute disk; a support having bearings in which said trunnions are mounted; a gear segment on one trunnion; and a rotatable worm meshing with said gear segment.

13. In a device of the class described, the combination of a casing having a peripheral discharge opening; a revolute disk within said casing provided with means for pro-

jecting a ball through said opening; means for feeding balls into the said casing at a point at one side of the axis of rotation of said disk; means for rotating said disk at a high rate of speed; a supply hopper for the balls; a revolute grooved member in said hopper; and a tube therefrom to said ball feeding means.

14. In a device of the class described, a casing; a revolute shaft extending through said casing; a disk provided with two oppositely disposed spiral members; means for feeding balls to the inner end of one of said spiral members; and means for securing said disk to said shaft whereby either of said spiral members may be placed in operation.

15. In a device of the class described, a casing; a revolute shaft extending through said casing and provided with a peripheral flange; a disk provided with two oppositely disposed spiral members; means for feeding balls to the inner end of one of said spiral members; and means for securing said disk to the flange of said shaft whereby either of said spiral members may be placed in operation.

16. In a device of the class described, a revolute shaft; a disk secured thereto; a spiral member thereon; a casing enclosing said disk including in part an annular ring having a peripheral discharge opening therein and a cover plate therefor, said ring having a plurality of spaced bolt holes for each bolt hole in said cover plate; bolts for securing said cover plate to said ring; and means carried by said cover plate for delivering a ball into said casing in the path of said spiral member.

17. In a device of the class described, a revolute shaft; a disk secured thereto; a spiral member thereon; a casing enclosing said disk including in part an annular ring having a peripheral discharge opening therein and a cover plate therefor, said ring having a plurality of spaced bolt holes for each bolt hole in said cover plate; bolts for securing said cover plate to said ring; means carried by said cover plate for delivering a ball into said casing in the path of said spiral member; and graduations on said ring opposite one set said bolt holes.

18. In a device of the class described a revolute shaft; a disk secured thereto and revolute therewith; a spiral member on said disk; a casing enclosing said disk and provided with a peripheral discharge opening; a tubular member secured to and extending through the cover of said casing, the inner wall of said tubular member being provided with a helical groove having a plurality of turns of the same diameter and a single larger turn at the lower end having a greater diameter; means for feeding balls to the upper end of said tubular member;

and a member on the upper end of said shaft projecting into the bore of said tubular member.

19. In a device of the class described, a revolute shaft; a disk secured thereto and revolute therewith; a spiral member on said disk; a casing enclosing said disk and provided with a peripheral discharge opening; a tubular member secured to and extending through the cover of said casing, the inner wall of said tubular member being provided with a helical groove having a plurality of turns of the same diameter and a single larger turn at the lower end having a greater diameter; means for feeding balls to the upper end of said tubular member, and a member on the upper end of said shaft projecting into the bore of said tubular member and provided with a semi-cylindrical groove extending downwardly from the upper end and curved outwardly at its lower end with its lowest part coinciding with the lower inner wall of said casing.

20. In a device of the class described, a revolute shaft; a disk secured thereto and revolute therewith; a spiral member on said disk; a casing enclosing said disk and provided with a peripheral discharge opening; a tubular member secured to and extending through the cover of said casing, the inner wall of said tubular member being provided with a helical groove having a plurality of turns of the same diameter and a single larger turn at the lower end having a greater diameter; means for feeding balls to the upper end of said tubular member and a member on the upper end of said shaft projecting into the bore of said tubular member and provided with a semi-cylindrical groove extending downwardly from the upper end and curved outwardly at its lower end with its lowest part coinciding with the lower inner wall of said casing; and means in said groove above the lower turn of said helical groove for forcing a ball out of alignment with the axis of said shaft.

21. In a device of the class described, a revolute shaft; a disk secured thereto and revolute therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through which the balls are delivered to said tubular member; a plate in which the opposite end of said tube is mounted, said plate having a spiral groove therein; and a hopper for the balls superimposed upon said plate and adapted to deliver balls to said spiral groove.

22. In a device of the class described, a revolute shaft; a disk secured thereto and

revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through which the balls are delivered to 5 said tubular member; a plate in which the opposite end of said tube is mounted and adapted to be oscillated; said plate having a spiral groove therein; and a hopper for the balls superimposed upon said plate and adapted to deliver balls to said spiral groove.

23. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through which the balls are delivered to 10 said tubular member; a plate in which the opposite end of said tube is mounted, said plate having a spiral groove therein gradually decreasing in depth to the upper surface of said plate; and a hopper for the balls superimposed upon said plate and adapted to deliver balls to 15 said spiral groove.

24. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through which the balls are delivered to 20 said tubular member; a plate in which the opposite end of said tube is mounted, said plate having a spiral groove therein; a hopper for the balls superimposed upon said plate; and a revoluble member in said hopper adapted to deliver balls to said spiral groove.

25. In a device of the class described, a

revoluble member in said hopper provided with a plurality of peripheral grooves adapted to deliver balls to said spiral groove.

26. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through which the balls are delivered to 55 said tubular member; a plate in which the opposite end of said tube is mounted, said plate having a spiral groove therein gradually decreasing in depth to the upper surface of said plate; and a hopper for the balls superimposed upon said plate and adapted to deliver balls to 60 said spiral groove.

27. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through 65 which the balls are delivered to said tubular member; a plate in which the opposite end of said tube is mounted, said plate having a spiral groove therein; a hopper for the balls superimposed upon said plate; and a revoluble member in said hopper adapted to deliver balls to 70 said spiral groove.

28. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through 75 which the balls are delivered to said tubular member; a plate in which the opposite end of said tube is mounted, said plate having a spiral groove therein; a hopper for the balls superimposed upon said plate; and a revoluble cone-shaped member in said hopper provided with a plurality of peripheral grooves extending upwardly with shallow upper ends, said grooves in the rotation of 80 said cone-shaped member being adapted to deliver balls to said spiral groove.

29. In a device of the class described, a revoluble shaft; a disk secured thereto and revoluble therewith; a spiral member on said disk; a casing enclosing said disk and provided with a peripheral discharge opening; a tubular member secured to and extending through the cover of said casing; means within said tubular member for directing a ball to the interior of said casing in the path of said spiral member; a tube through 85 which the balls are delivered to said tubular member; a plate in which the opposite end of said tube is mounted, said plate having a spiral groove therein; a hopper for the balls superimposed upon said plate; and a revoluble cone-shaped member in said hopper provided with a plurality of peripheral grooves extending upwardly with shallow upper ends, said grooves in the rotation of 90 said cone-shaped member being adapted to deliver balls to said spiral groove.

Signed by me at 4 Post Office Sq., Boston, Mass. this 11th day of January 1918.
